UNITED STATES PATENT OFFICE.

CHARLES E. GEIGER, OF LOUISVILLE, KENTUCKY, ASSIGNOR OF ONE-THIRD TO HIMSELF, ONE-THIRD TO WILLIAM E. KOOP, AND ONE-THIRD TO G. WALKER FISKE, ALL OF LOUISVILLE, KENTUCKY.

DRIER.

940,144.

Specification of Letters Patent.

Patented Nov. 16, 1909.

Application filed December 8, 1908. Serial No. 465,779.

To all whom it may concern:

Be it known that I, CHARLES E. GEIGER, a citizen of the United States, residing at Louisville, in the county of Jefferson and 5 State of Kentucky, have invented new and useful Improvements in Driers, of which the following is a specification, reference being had to the accompanying drawings, forming a part thereof.

10 The purpose of this invention is to provide an improved drier especially adapted for the purpose of drying grains, small fruits, sand and the like.

It consists in the features of construction 15 shown and described as indicated in the claims.

In the drawings:—Figure 1 is an end elevation of a drier embodying this invention. Fig. 2 is a longitudinal vertical section at 20 the line 2—2 on Fig. 1. Fig. 3 is a transverse vertical section at the line 3—3 on Fig. 2. Fig. 4 is a view similar to Fig. 2 showing a modification. Fig. 5 is a similar view showing an additional modification.

25 The structure illustrated in these views comprises two opposite chambered heads, 1 and 2, which are connected by horizontal pipes, 3, arranged in two parallel tiers or columns. These heads form two ends of the 30 casing, of which the bottom is formed by a trough, 4, a top, 5, being also provided, which is longitudinally rifted at 6, and above the rift there is mounted a spiral conveyer, 7, into which the material to be treated 35 is delivered and by which it is distributed longitudinally of the drier casing for delivery in a stream or shower extending over the entire length of the same. Immediately below the discharge rift of this conveyer, 40 which is directly above a line between the two tiers or columns of pipes, 3, there is an inverted V-shaped deflector, 6, for parting the descending stream of material and deflecting the parts to the opposite outer sides 45 of the two tiers of pipes, 3. This deflector, 6, may form a part of a complete jacket, 8, inclosing both tiers of pipes and defining a heating chamber in which such pipes are the heating element. This jacket is made of 50 perforated sheet metal so as to permit comparatively free but somewhat restricted communication from the space within to the space without,—that is, from the heating compartment to the drying compartment.

The outer side walls of the structure preferably consist of inclined slats, 9, which constitute deflecting plates for the material to be dried as it descends within the drying chamber, and which form between them passages for the escape of vapor and air from 55 the material. Below the two tiers of pipes, 3, a pipe, 10, extends parallel to them leading from a fan or blower, 11, located outside the inclosed structure. This pipe, 10, is perforated on the upper side for discharge 60 of the air upward between the two tiers of pipes, 3. In order to cause the air to circulate most thoroughly around and between the pipes, there is preferably located in the 65 interval between each four pipes, two in each tier, a V-shaped deflector, 13. These deflectors are supported at the ends by the 70 headers, 1 and 2, and are spaced away from all four of the pipes between which they are located respectively, so that the air can pass 75 above as well as below them in circulating past the pipes. The material to be treated, when delivered through the rift, 6, and parted into two streams passing down at opposite sides of the heating compartment, being 80 in some cases quite moist, is preferably exposed to the action of stirrers, 14, which extend longitudinally parallel with the pipes, 3, and are rotated vertically for keeping the 85 material agitated and preventing it from becoming massed together. The slats or deflecting plates, 9, tend to cause the material as it descends to drift inward toward the 90 pipes, 3, and in the absence of any means to prevent such result, the entire mass would tend to move down along the wall of the 95 jacket, 8, with the result that the outer portion would be less dried than the inner portion. To prevent such result and insure equal drying of all parts of the material, alternate stirrers, 14, are rotated in opposite 100 directions, so that, for example, the first stirrer tends to carry the material outward on to the upper deflecting plate, 9, by which it is directed inward over the second stirrer which rotates inwardly at the upper side and carries it farther inward against the jacket, and at its lower side tends to carry it outward. The third stirrer rotates outwardly at its upper side, the second and 105 third stirrers together thus causing the material to be carried away from the jacket outwardly and delivered on to one of the de-

flecting plates or slats, 9, by which it is again directed inward against the jacket. Any number of stirrers may be employed distributed throughout the height of the structure, commencing at the upper part as shown, but for many materials it would not be necessary to continue them more than one-third of the way down the structure, because by the time the material has been exposed to the drying action for that distance, it will be sufficiently dry to be no longer adhesive to an extent creating liability to massing. In Figs. 1 and 2, therefore, only three stirrers on each side are shown at the upper 15 part of the structure. In order that the material may be controlled in its descent through the drying chamber and so retained in it long enough for complete drying, the discharge therefrom at the lower end is controlled by means of a rotary valve, 16, which 20 by its blades, 16^a, substantially bars the passage or throat-way between the lowest of the pipes, 3, and the trough or converging bottom, 4, permitting the material to pass as it 25 is carried in the apex or intervals between consecutive blades, and thus delivering it in measured quantities at a rate determined by the rate of rotation of said valve device. Upon passing these rotary valves, the material 30 is received in the lower part of the trough bottom, 4, directly under the pipe, 10. In this lower part of the trough, there is mounted a screw conveyer, 17, by which the material is fed longitudinally of the 35 trough for delivery at one end thereof.

For rotating the two conveyer screws, 7 and 17, the stirrers, 14, and the valves, 16, the shaft of the spiral, 7, carries at one end outside the chamber fast and loose pulleys, 40 18, 18^a, for receiving power by belt, and at the opposite end outside the chamber there is fast on the shaft a sprocket wheel, 19, which drives a chain, 20, passing about gears, 21, on the ends of the stirrer shafts, 45 14^a, the chain being zigzagged around the gears, as shown in Fig. 1, to give alternate stirrers each side opposite rotation as described. On the shaft there is mounted another fixed sprocket wheel, 22, from which 50 a chain, 23, passes about a sprocket wheel, 24, on the corresponding end of the shaft of the feed screw, 17, of the discharge conveyer. For rotating the two rotary valves, 16, there is mounted on the shaft, 7^a, between the two sprocket wheels, 19 and 22, an eccentric, 25, from whose outer element, 25^a, a connecting rod, 26, extends to the lever arm, 27, mounted for rocking about the axis of one of the rotary valves, 16, and having 55 connected with it a pawl, 28, for engaging a ratchet disk, 29, on the shaft of said valve. On the same shaft there is a sprocket wheel, 30, and on the shaft of the other valve, 16, a similar sprocket wheel, 30, which said similar sprocket wheels are connected by a chain,

31, giving them equal and simultaneous movement. The rate of feed effected by the rotation of the valve is regulated by adjusting the end of the connecting rod, 26, in the slot, 27^a, of the lever, 27, to vary the stroke 70 of the pawl.

In Fig. 4 there is illustrated a slight modification consisting in dispensing with the jacket, 8, for inclosing the heating chamber and substituting for a similar purpose perforated diaphragm strips, 8^a, interposed between the consecutive pipes of each tier, so that with the pipes these partitions make an inclosing but apertured wall of a heating chamber. The chief difference of result 80 which follows this change of structure is that in the structure shown in Fig. 4, the pipes on their outer side are directly exposed to the material to be dried and radiate heat somewhat more rapidly thereto, causing the drying to proceed faster at the earlier stages. One form will be preferable for some substances and the other form for others.

In Fig. 5 there is illustrated a further 90 modification which consists in omitting the lower group or section of pipes, 3, leaving the lower part of the chamber occupied by the heating pipes vacant and devoid of a heating means, so that the air delivered 95 through the pipe, 10, into that chamber is not immediately heated, but is adapted to operate for cooling the grain through which it is discharged at the lower part of the chamber before it reaches the lowest of the 100 heating pipes. This is desirable in using a drier of this character for drying whole grain, which must be well cooled before it will be in condition for storage.

I claim:—

1. A drier having, in combination, a heating element consisting of a pipe system through which the heating medium is supplied, the pipes of the system being disposed and connected to form between them a 110 passage for a drying element; a drying chamber within which such heating element is contained, having means for controlling the advance through it of the material treated; means for discharging a drying medium within the material in the drying chamber at distributed points in its height, and means for permitting free air escape from such chamber through the outer walls thereof at distributed points in the latter. 115

2. A drum having in combination a heating compartment comprising a pipe system through which the heating medium is supplied, the pipes of the system being disposed and connected to form between them a 120 passage for a drying element; a drying chamber within which such heating compartment is contained having means for controlling the advance through it of the material treated, and means for causing forced 130

- circulation of a drying medium from below upward through the heating compartment, said compartment having limited communication with the space through which the material passes in the drying chamber distributed throughout its height, said drying chamber having free outer air communication through its outer side walls distributed throughout their height.
5. In a drier having, in combination, a heating element comprising a pipe system through which the heating medium is supplied, the pipes of the system being disposed and connected to form between them a passage for a drying element; a drying chamber within which such heating element is contained, provided at its upper end with an inlet for the material to be treated and at its lower end with a discharge passage; a 10 valve device for controlling the discharge of the material through such passage; means for discharging a drying medium within the material in the chamber at distributed points in its height, and means for permitting the escape of air from said chamber at distributed points in the height of the latter.
15. A drier having, in combination, a heating element consisting of a pipe system through which the heating medium is supplied, the pipes of the system being disposed and connected to form between them a passage for a drying element; a drying chamber within which such heating element is contained, provided at its upper end with an inlet and at its lower end with a discharge passage for the material; means for supplying a drying medium to said passage between the system of pipes, the disposition 20 and connection between said pipes being such as to permit the discharge of the drying medium from said passage into the drying chamber at distributed points in the height of the latter, and means for permitting free air escape from said drying chamber.
25. A drier having, in combination, a heating element comprising a pipe system in which the heating medium circulates; a drying chamber within which such heating element is contained, provided at its upper end with an inlet for the material to be treated and at its lower end with a trough into which the material is discharged; a rotary valve device controlling the entrance to such trough, and a conveyer in the trough to drive the material therefrom.
30. A drier having, in combination, a heating element comprising a pipe system in which the heating medium circulates; a drying chamber within which such heating element is contained provided at the upper end with an inlet for the material to be treated and at the lower end with a discharge passage; a rotary valve which con- 35 trols the discharge of the material through such passage; means for rotating the same and for regulating the speed of such rotation.
35. A drier having, in combination, a heating element comprising a pipe system in which the heating medium circulates; a drying chamber within which such heating medium is contained; a supply feeding device for delivering the material into the chamber at the upper end, said chamber having a discharge passage at the lower end; a rotary valve for controlling the discharge of the material through such passage; means for rotating such valve and means for regulating the speed of rotation relatively to that of the supply feeding device.
40. A drier having, in combination, a heating element comprising a pipe system in which the heating medium circulates; a drying chamber within which such heating element is contained, provided at its upper end with an inlet for the material to be treated and at its lower end with a discharge passage; a valve device for controlling the discharge of the material through such passage; means for discharging a drying medium into the heating chamber, the wall of the latter being apertured for discharging such medium into the drying chamber at points distributed throughout the height, and means for permitting the discharge of air out of said drying chamber at points distributed throughout the height.
45. A drier having a heating element comprising a pipe system in which the heating medium circulates; a drying chamber within which such heating element is contained, provided at its upper end with a supply inlet for the material to be treated, and at its lower end adapted for the discharge of the material; means for discharging a drying medium within the material in said chamber at distributed points in its height; means for permitting the escape of such medium from said drying chamber at distributed points in its height; a rotary valve device controlling the discharge of the material at the lower end of the drying chamber; stirrers extending longitudinally of the chamber and distributed through the upper portion thereof, and means for rotating the stirrers and the discharge-controlling device.
50. A drier having, in combination, a heating compartment comprising a pipe system in which the heating medium circulates; a drying chamber within which such heating compartment is contained, provided at its upper end with a supply inlet for the material to be treated and adapted at its lower end for discharge of the material; means for causing circulation of a drying medium from below upward through the

heating compartment, said compartment having limited communication with the drying chamber for the passage of such drying medium into the latter chamber at distributed points in the height thereof; a rotary valve device which controls discharge of the material from the lower end of the drying chamber, and means for operating and regulating such device.

10 11. A drier having a heating element consisting of a pipe system in which the heating medium circulates; a reticulated jacket inclosing such heating element and forming a heating compartment; a drying chamber within which such heating compartment is contained having means for controlling the downward advance through it of the material treated; means for causing forced circulation of a drying medium from below 20 upward through the heating compartment, the reticulated jacket of said compartment affording distributed throughout the height restricted communication of said compartment with the drying chamber exterior thereto, and means for the escape of the 25 drying medium from the drying chamber.

12. A drier having a heating element consisting of a pipe system in which the heating medium circulates longitudinally and 30 progressively downward; a drying chamber within which such heating element is contained having at the upper end an inlet for the material to be treated and at the lower end means for discharge of such material; 35 means for controlling the advance of the material through said drying chamber; means for agitating the material during the initial part of its advance.

13. A drier having a heating compartment 40 comprising a pipe system in which the heating medium circulates; a drying chamber within which such compartment is contained; means for causing forced circulation of a drying medium from below upward through the heating compartment, the latter having reticulated walls for vertically distributed communication with the drying chamber and the discharge of the drying medium into the latter, and deflecting plates 50 in the drying chamber for driving the descending material inward toward the heating compartment, the outer walls of the drying chamber being apertured, and said deflecting plate leading to such apertures 55 for deflecting the drying medium there- toward.

14. A drier having a heating compartment comprising a pipe system in which the heating medium circulates; a drying chamber 60 within which such compartment is contained; means for causing forced circulation of a drying medium from below upward through the heating compartment and therefrom into the drying chamber, the latter having deflecting plates for direct-

ing the descending material inward and the ascending drying medium outward; a plurality of rotary stirrers, one above another, extending longitudinally and rotating vertically in said drying chamber, and means 70 for rotating alternate stirrers in opposite directions.

15. A drier having a heating compartment comprising a pipe system in which the heating medium circulates; a drying chamber within which such compartment is contained; means for causing forced circulation of the drying medium upward through the heating compartment and therefrom into and through the drying chamber; a plurality of rotary stirrers extending longitudinally in the drying chamber; means for revolving alternate stirrers in opposite directions, and inclined plates outside the stirrers for deflecting the descending material inward.

16. A drier having a heating compartment, a drying chamber within which such compartment is contained, said drying chamber having inlet at the upper end and discharge at the lower end for the material treated; means for controlling the rate of advance of the material downward through said drying chamber comprising a rotary valve device at the discharge thereof; a 95 pawl and ratchet for rotating such device; a lever for operating the pawl; a rotating shaft and a connecting rod therefrom for oscillating the lever, the connection of said arm with said lever being adjustable along 100 the lever to vary the feeding stroke of the pawl.

17. A drier comprising a chamber and a heating compartment therein; a supply trough at the top of the chamber extending 105 longitudinally thereof; discharging downwardly thereinto throughout its length; a chamber having a longitudinally extending trough at the bottom arranged for discharge at one end; spiral conveyers in the troughs 110 respectively for advancing the material longitudinally thereof; means for rotating said conveyers; a rotary valve device for controlling the delivery of the material into the trough at the bottom; means for rotating 115 such valve device connected with the means for rotating the spiral conveyers, and means for adjusting the connections to vary the speed of the rotating device relatively to the conveyers.

18. A drier having, in combination, a compartment comprising at the upper part a pipe system in which the heating medium circulates, and comprising below the pipe system a portion devoid of heating means; a 125 drying chamber within which such compartment is contained provided at its upper end with a supply inlet for the material to be treated, and having at its lower end means for the controlled discharge of the material, 130

and means for causing circulation of air from below upward through said compartment, the latter having limited communication with the drying chamber for the passage of air into the latter at distributed points in the height thereof.

19. A drier having, in combination, a heating element which consists of a pipe system in which the heating medium circulates; 10 a reticulated jacket forming a compartment inclosing at its upper part such heating element, and having at its lower part, devoid of heating means, a drying chamber within which such compartment is contained, said 15 chamber being provided with means for controlling the downward advance through

it of the material treated, and means for causing forced circulation of air from below upward through said compartment, the reticulated jacket of said compartment affording, distributed throughout the height, restricted communication of said compartment with the drying chamber exterior thereto.

20 In testimony whereof, I have hereunto set my hand, in the presence of two witnesses, 25 at Chicago, Illinois, this 17th day of November, 1908.
